UNITED STATES PATENT OFFICE.

FRANK HUBKA AND ANTON HUBKA, OF CHICAGO, ILLINOIS.

WINDOW-SCREEN.

SPECIFICATION forming part of Letters Patent No. 318,988, dated June 2, 1885.

Application filed June 6, 1884. (No model.)

To all whom it may concern:

Be it known that we, FRANK HUBKA and ANTON HUBKA, citizens of the United States, residing at Chicago, in the county of Cook and 5 State of Illinois, have invented certain new and useful Improvements in Window-Screens, which are fully set forth in the following specification, reference being had to the accompanying drawings, forming a part hereof, and 10 in which—

Figure 1 shows a window on the interior of a room, provided with our improved screen. Fig. 2 is an enlarged view of one of the lower corners of the screen and part of the adjustable 15 piece attached thereto. Fig. 3 shows the entire adjusting-piece, partly covered by the upper corner of the screen. Fig. 4 shows a sectional view of the adjusting-piece *i*, the frame *e*, and a wire, *m*, taken anywhere between the 20 bolts *j* across the frame.

Like letters of reference indicate like parts.

The object of our invention is to provide a window-screen which shall, first, cover either the upper or lower sash, or be adjustable at 25 any point between the limits of its motion; second, be adjustable to the varying width of windows; and, third, which shall have its own removable ways or supports upon which it moves.

In the drawings, *a* represents the window-casing, into the frame of which are placed supports or screw-eyes *b*. Into said screw-eyes are placed rods *c*, threaded and provided with nuts at each end, as shown. The rods *c* may 30 be fastened to their places in any other well-known and desirable manner. Said rods are placed as near to the window-sash *d* as will be necessary to cause the frame *e* of the screen to slide closely against the sash, and said frame 35 is provided with eyes *f* on its inner side, with holes through them, through which loosely pass the rods *c*, on which the screen moves up and down.

To the inner and lower corners of the frame *e* are attached pointed spring-bolts *g*, which 45 pierce into the window-frame to hold the screen at any desired point.

Near the upper and lower ends of the vertical sides of the screen-frame *e* are transverse slots *h*, and upon the back or outer side of said 50 frame is placed a sheet-metal plate, *i*, also provided with transverse slots *h'*, registering with the slots *h*, and through which bolts *j*, with thin flat heads, are passed inward and provided on their inner ends with butterfly-nuts 55 *k*. By means of said adjustable piece *i* the space covered by the frame *e* may be considerably increased on both of its edges and the frame made to fit closely into the sides of the window-frame. The motion of the piece is 60 shown in dotted outlines.

The frame *e* has a stout wire, *l*, forming a frame to stiffen it, running all around its exterior. The frame *e* is also made preferably 65 of sheet metal.

This construction enables the use of the screen for the upper sash as well as the lower, so that the lower sash may be closed and the upper one open and screened, or vice versa, 70 at pleasure.

What we claim is—

1. A rigid window-screen provided with eyes *f* upon one of the face sides of the frame, and bolts *g* upon its lower edge, in combination with rods *c*, substantially as specified. 75

2. A window-screen having a rigid frame upon which there are eyes *f* on one of its faces, in combination with adjustable rods *c*, passing through said eyes, and supports *b*, substantially as specified.

FRANK HUBKA.
ANTON HUBKA.
